Primary Examiner — Marie D. Fast Horse(74) *Attorney, Agent, or Firm* — Maier & Maier, PLLC(57) **CLAIM**

The ornamental design for an intelligent POS terminal device, as shown and described.

DESCRIPTION

FIG. 1 is a front elevational view of an intelligent POS terminal device showing our new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a front perspective view thereof; and,
FIG. 8 is a rear perspective view thereof.
